CLAIM

The ornamental design for a part of spectacle frames as shown and described.

DESCRIPTION

FIG. 1 is a top view of the part of spectacle frames;
FIG. 2 is a perspective view thereof;
FIG. 3 is a bottom view thereof;
FIG. 4 shows the part of spectacle frames of FIG. 1 on a spectacle frame;
FIG. 5 is a right-side view of the part of spectacle frames of FIG. 1;
FIG. 6 is a front view thereof; and,
FIG. 7 is a rear view thereof.

The broken lines are for the purpose of illustrating environmental structure only and form no part of the claimed design.
